UNITED STATES PATENT OFFICE.

PAUL MACGAHAN, OF EAST PITTSBURGH, PENNSYLVANIA, ASSIGNOR TO WESTINGHOUSE ELECTRIC & MANUFACTURING COMPANY, A CORPORATION OF PENNSYLVANIA.

RELAY.

Application filed June 10, 1925. Serial No. 36,109.

My invention relates to electroresponsive devices, and particularly to electromagnetic relays.

One object of my invention is to provide a relay that shall be particularly adapted for the short-circuit protection of distribution systems in which the adjustment remains unchanged for different values of load current traversing the system.

Another object of my invention is to provide a surge-responsive relay that shall have two cooperating members normally in a definite relation, irrespective of the current traversing the device, the normal relation of which is changed upon a surge of current through the device.

A further object of my invention is to provide a relay that shall have two independently movable elements operated by an induction-motor means and operatively connected by a resilient means and so damped in operation as to obtain a predetermined relative movement thereof, depending upon the energization of the actuating means.

It has been customary to employ over-current relays for the short-circuit protection of distribution systems which operate when the current traversing the system reached a predetermined abnormal value.

In many instances, however, such relays are unsatisfactory because of the variation in the value of the short-circuit current on account of changes in connected generator capacity. If the generator capacity of a system is reduced during periods of light load, which may recur daily, it is evident that the short-circuit current during such periods may be less or slightly greater than the load current during the peak load. The use of an over-current relay in such a system, therefore, provides no protection during periods of light load unless the adjustment of the relay is changed by the station operator.

In accordance with my invention, a relay which is responsive to short-circuits or sudden surges of current only is provided to obviate the aforementioned difficulties. The relay comprises two contact members having normally a definite spaced relation, irrespective of the value of the load current. The

contact members are responsive to the current traversing the relay but have different time characteristics. Upon a surge of current, therefore, the contact members are engaged to close a circuit for tripping a circuit-interrupter or other purpose. Preferably, both contact members are driven by a single actuating means, a resilient connection being interposed between the actuating means and the contact member having the heaviest damping.

The nature of my invention may be understood by reference to the accompanying drawing, the single figure of which is a view, in perspective, of a relay embodying my invention.

Referring to the drawing, the relay comprises an actuating means 1 energized from a circuit 2 and controlling contact members 3 under predetermined conditions in the circuit. The actuating means is of the induction-motor type and comprises an electromagnet 4 connected to a current transformer 5 in the circuit 2 and controlling a pivoted armature member 6. A spring 7 and a damping magnet 8 are provided for controlling the movement of the armature member 6. Connected to the armature member 6 through a spring 9 is a second pivoted disc member 10, one of the contact members 3 being operatively connected to, and movable with, each disc member. Suitable damping means, such as the damping means 11, are provided for controlling the movement of the disc member 10, the damping action on the disc member 10 being greater than that on the disc member 6. The disc member 10 may have a greater mass than the disc member 6 or may be mechanically or electrically damped instead of, or in addition to, being magnetically damped.

The electromagnet 4 is energized in accordance with the current traversing the circuit 2 and actuates the armature member 6 against the restraining torque of the spring 7 an amount proportional to the current in said circuit. The second disc member 10, being controlled by the armature member 6, also assumes a position dependent upon the current flowing in the circuit 2, but, by reason of the fact that it is heavily

damped and is driven through the resilient connection 9, the movements of the disc member 10 are retarded with respect to those of the armature member 6.

5 The contact members 3 traverse the same path and, under normal current conditions, have a definite spaced relation with respect to each other. If the current traversing the circuit 2 changes by reason of a change in 10 load thereon, the relation of the contact members 3 remains unchanged, although, temporarily, the contact members approach or recede from each other, depending upon the amount of the change in load and whether 15 the change is an increase or a decrease.

If a short-circuit occurs in the circuit 2, however, the sudden increase of current actuates the armature member 6 in such direction as to cause the contact members 3 20 to engage. The engagement of the contact members 3 may be utilized to open the circuit 2, to operate an alarm, or for any other desired purpose.

The operation of the relay is not affected 25 by the load on the circuit 2 or by the connected generator capacity. In many applications of protective relays, this feature is important. For instance, if the circuit 2 is a railway distribution circuit on which the 30 load varies widely, it is desirable to provide a relay which is as sensitive to short-circuits during periods of light load as during periods of heavy load. Furthermore, if the connected generator capacity is reduced 35 during periods of light load, it may happen that the short-circuit current during such periods is even less than the full-load current during a peak load. It is apparent that the relay described is satisfactory for this application, inasmuch as the adjustment is not 40 affected by the load, and the engagement of the contact members is effected upon a short-circuit or heavy surge of current, irrespective of the actual value of such current.

45 While I have illustrated one embodiment of my invention, in order that the same may be readily understood, I do not consider that

it is limited to the precise details shown and described, and, accordingly, I do not wish to be limited except as indicated in the appended claims.

I claim as my invention:

1. In combination with an electric circuit, a relay comprising a rotatable armature having a contact secured thereto, inductive means for effecting the rotation thereof responsive to load conditions in said circuit, a second rotatable armature having a contact secured thereto in the path of movement of said first contact, a resilient driving connection between said armatures, and means whereby said contacts are maintained in spaced relation during normal variations in load on said circuit and are moved into contacting relation responsive to an abnormal increase in load.

2. In combination with an electric circuit, an armature rotatable in response to the value of current traversing said circuit, a contact member secured to said armature, a second contact member and means for mounting the same for movement in the path of movement of the first contact, and means for maintaining said contacts in spaced relation during normal variations in load, and for moving said contacts into operative engagement in response to an abnormal surge in said circuit.

3. A relay comprising a movable armature, inductive means for effecting the movement thereof, a contact member secured to said armature, a second contact member, means for mounting said second contact for movement in the path of movement of the first contact, a resilient driving connection between said armature and second contact, and means whereby said contacts are maintained in spaced relation during normal variations in the energization of said inductive means and are moved into contacting relation upon the occurrence of an abnormal variation.

In testimony whereof, I have hereunto subscribed my name this 5th day of June, 1925.

PAUL MACGAHAN.
